CLAIM

The ornamental design for a multifunction telecommunication apparatus, as shown and described.

DESCRIPTION

FIG. 1 is a top plan view of a multifunction telecommunication apparatus showing my new design;
FIG. 2 is a front elevational view thereof;
FIG. 3 is a right side elevational view thereof;
FIG. 4 is left side elevation view thereof;
FIG. 5 is a rear elevational view thereof;
FIG. 6 is a perspective view thereof with the handset placed in the telephone receptacle; and,
FIG. 7 is a perspective view according to FIGS. 1 through 6 with the handset removed from the receptacle and placed on its side to show the design of the underside of the handset and design of the receptacle.
